UNITED STATES PATENT OFFICE.

PATRICK H. SUGRUE, OF WASHINGTON, DISTRICT OF COLUMBIA.

FURNACE-ROOF.

1,032,960.

Specification of Letters Patent.

Patented July 16, 1912.

Application filed May 27, 1910. Serial No. 563,757.

To all whom it may concern:

Be it known that I, PATRICK H. SUGRUE, of Washington, District of Columbia, have invented certain new and useful Improvements in Furnace-Roofs; and I do hereby declare the following to be a full, clear, and exact description of the invention, such as will enable others skilled in the art to which it appertains to make and use the same.

10 Heretofore considerable difficulty has been experienced by the liability to collapse of the roofs or arches of furnaces employed in connection with high pressure boilers. The intense heat frequently causes 15 an appreciable vibratory motion in the roofs or arches resulting in the loosening of the fire-bricks and the collapse of the structure.

The object of my invention is to obviate 20 these difficulties and at the same time enable the roof to be built as close to the grate as desired, without danger of collapsing. And a further object is to so form the bricks or tiles 25 that they may be employed to produce a roof having either a uniform height from the grate or a stepped construction, the latter being either uniform or irregular, as conditions may require.

The invention will be hereinafter fully 30 set forth and particularly pointed out in the claims.

In the accompanying drawings, Figure 1 is a sectional view of a portion of a furnace having a roof with an uneven or broken 35 surface. Fig. 2 shows two bricks, with parts in dotted lines. Fig. 3 shows a series of bricks in plan view. Fig. 4 is a perspective of a brick of ordinary proportions. Fig. 5 shows a larger brick. Fig. 6 shows a 40 half-size brick. Fig. 7 shows a slight modification.

In carrying out my invention, I preferably make each brick or tile oblong, and but of little thickness. On one of the flat sides 45 I form two longitudinally extended, diagonal grooves 1 and 2 (see Fig. 4) which preferably extend the full length of the brick and intersect the upper and lower edges thereof. On the opposite face of the brick, 50 and parallel with the respective grooves, are two ribs 3 and 4. The groove 2 is set nearer to the adjacent longitudinal edge of the brick than the groove 1 is relatively to the

other longitudinal edge. The ribs 3 and 4 correspond to the respective grooves. In 55 this way I form wedging portions of different widths. While two grooves and two ribs in each brick are sufficient for all ordinary purposes, yet in some instances the bricks may be of extra width and equipped 60 with three grooves or ribs on its opposite sides (see Fig. 5) but the number is immaterial. In this event the end grooves and ribs maintain the stated distances from the adjacent longitudinal edges of the bricks. 65

In practice, an end row of bricks may be made up of alternate full and half width bricks, the latter, which are shown at 5, (Figs. 3 and 6) serving merely as spacers between the bricks of the first row, it being 70 necessary to space such bricks to provide for the interlocking therewith of the bricks of the next row, the full width bricks of the first row in turn serving as spacers for the bricks of the second row. Or if the row be 75 made up primarily of bricks of extra length, as shown at 6 (Figs. 3 and 5) the bricks of normal size form the spacers. Either arrangement may be observed throughout the construction of the roof, and to close the 80 spaces between the projecting portions of the bricks of the last row, bricks of a smaller size than those which project are employed for that purpose.

Assuming that the first row of bricks has 85 been positioned, and is suitably supported at its opposite ends by the ordinary brick walls, in building up the second row the bricks are, one at a time, passed downwardly through the vertical passages between the opposed faces of the projecting 90 portions of the full width bricks of the first row. As each brick moves downwardly, it will also move horizontally until arrested by engagement with the longitudinal 95 edge of a brick of the adjacent row. If the ribs 3 of the bricks of the second row are caused to engage grooves 1 of the bricks of the first row, or the ribs 4 to engage the grooves 2, the bricks of the second row will 100 be flush with the bricks of the first row, that is, the opposite longitudinal edges of bricks in the same vertical plane will not be brought together until the bricks of the second row have traveled the length of the 105 bricks. This arrangement is observed in

forming two or more or all the rows with their lower edges on the same horizontal plane. When, however, it is desired to obtain a stepped or broken lower surface, that is, with the lower edge of each row on a different plane from the next adjacent row, the ribs 4 are caused to enter grooves 1, or ribs 3 to enter grooves 2, and hence the opposed longitudinal edges of bricks in the same vertical plane will be caused to engage before the bricks which are being inserted can travel the distance of their full length, as shown in full and dotted lines, Fig. 2. In Fig. 1 I have shown the roof made up first of a series of stepped rows; then a series of unstepped rows; then a second series of steps, and finally a series of unstepped rows, with their lower edges on uniform horizontal planes. Any desired arrangement may be observed, a change being effected by merely reversing, end for end, the bricks of one row relatively to those of the last previously formed row.

As before stated, the bricks may be employed in constructing a straight roof or an arch. When employed in arch structure a necessary number of wedge-like blocks will be required, as is customary.

The advantages of my invention will be apparent to those skilled in the art. It will be seen that the weight of the bricks themselves tend to tighten the locking engagement between the bricks of different rows, and hence it is impossible for the bricks to fall out of place so long as their lateral supports are not impaired. In consequence I can build the roof much closer to the grate than has heretofore been possible in furnaces constructed for high-pressure boilers, and which necessarily maintain a very high temperature. It is highly advantageous to build the roof close to the grate, but heretofore it has been practically impossible to bring it within the desired distance because of destruction thereof by the intense heat. This interlocking of the bricks of adjacent rows by the diagonally arranged ribs and grooves allows the bricks to have limited movements in opposite directions under the action of heat and cold without danger of throwing down the arch. Practice has demonstrated that high pressure boilers having arches constructed in accordance with my invention may be constantly operated under high heat, and the fire withdrawn without danger of impairing the arches. It will be seen that by forming different wedges by the respective ribs and grooves it is only necessary to invert the bricks of one row relatively to those of another row to produce a stepped construction. If desired in some instances a rib 8 and a groove 9 may be formed on the opposite narrow longitudinal edges of the bricks, as shown in Fig. 7, so that abutting longitudi-

nal edges may interlock. The number of ribs and grooves on the edges is immaterial.

I claim as my invention:—

1. A roof structure composed of rows of bricks, each row consisting of vertically-disposed spaced-apart bricks, the bricks of adjacent rows overlapping, and such overlapping portions having on both sides longitudinally extended interlocking wedging portions for drawing the bricks of each row toward the bricks of a previously formed row, the interlocking portions on both sides of each brick being parallel. 75

2. A roof structure composed of rows of bricks, each row consisting of vertically-disposed spaced-apart bricks, the bricks of adjacent rows overlapping, and each brick of each row having diagonally arranged longitudinally extended grooves on one side and ribs on the other side paralleling said grooves, such ribs and grooves extending throughout the length of each brick, a groove or grooves of the bricks of one row being designed to receive the rib or ribs of the bricks of the next adjacent row. 90

3. A roof structure composed of rows of bricks, each row consisting of vertically-disposed spaced-apart bricks, the bricks of adjacent rows overlapping, and such overlapping portions having throughout their lengths longitudinally extended interlocking wedging portions, the interlocking wedging portions of the bricks of one row differing in width from the interlocking wedging portions of the bricks of the adjacent row. 95

4. A roof structure composed of rows of bricks, each row consisting of vertically-disposed spaced-apart bricks, each having on one side throughout its length diagonally - arranged longitudinally - extended grooves, and on the other side, and parallel with the grooves, a corresponding number of ribs, the distance between one edge of the brick and the adjacent rib and groove 105 being greater than the distance between the other edge and the rib and groove adjacent thereto. 110

5. A brick having a plurality of interlocking parallel ribs and parallel grooves on 115 its opposite sides forming wedging portions of different widths, the interlocking portions on both sides of each brick being parallel.

6. A brick having on one side two parallel inclined grooves, one groove being nearer to the adjacent upright edge of the brick than the other groove is to the other upright edge, and two inclined ribs on the opposite side of the brick, said ribs respectively occupying the same positions relatively to the upright edges as stated in reference to the grooves. 120

7. In combination with lateral supports, a roof composed of rows of overlapping 130

bricks set on end; diagonally-arranged interlocking portions on the bricks of each row for causing the bricks of a row being positioned to move horizontally as they are lowered vertically.

8. A roof composed of rows of overlapping bricks set on end and of step-like formation, each brick having interlocking wedging portions, the width of one wedging

portion being greater than that of the co- 10 acting wedging portion.

In testimony whereof, I, have signed this specification in the presence of two sub-scribing witnesses.

PATRICK H. SUGRUE.
